A. W. HARRISON ET AL

COIN CONTROL MECHANISM FOR ELECTRIC CIRCUITS

Original Filed July 14, 1922

Fig. 2.

UNITED STATES PATENT OFFICE.

ARTHUR W. HARRISON, OF LOS ANGELES, AND FLOYD O. CHAFFEE, OF EAGLE ROCK, CALIFORNIA, ASSIGNEES TO FRED J. GOGGINS, OF LOS ANGELES, CALIFORNIA, AND FRANK W. KINNEY, OF CHICAGO, ILLINOIS.

COIN-CONTROL MECHANISM FOR ELECTRIC CIRCUITS.

Application filed July 14, 1922, Serial No. 574,997. Renewed October 5, 1925.

To all whom it may concern:

Be it known that we, ARTHUR W. HARRISON and FLOYD O. CHAFFEE, citizens of the United States, residing at Los Angeles and 5 Eagle Rock, respectively, in the county of Los Angeles and State of California, have invented new and useful Improvements in Coin-Control Mechanisms for Electric Circuits, of which the following is a specification.

This invention relates to coin control mechanism, for electric circuits, and has for its object to provide a coin control mechanism whereby an electric circuit can be 15 maintained closed for a predetermined length of time by and after the introduction of a suitable token, such as a coin.

A further object is to provide a coin control means and a combined switch and main 20 motor circuit whereby the motor in the circuit can be started and stopped after running a predetermined period.

Other objects will be made manifest in the following specification of an embodiment 25 of the invention illustrated in the accompanying drawings, in which

Figure 1 is a vertical section and partial elevation of the coin control instrument shown connected to an electric circuit in 30 diagram.

Fig. 2 is a plan and partial horizontal section of the coin control.

Fig. 3 is a side elevation of an instrument, such as a washing machine having a 35 motor to be controlled for a given time.

In the present embodiment of the invention the device consists of a shell 2 of flat cylindrical form and through which extends centrally a shaft 3 having a suitable gear train connection 4 with a motor 5 which is in the present instance utilized with a washing machine mechanism.

It is desirable to enable the running of the motor for a predetermined length of 45 time and then to automatically stop it, and this is accomplished by arranging within the shell 2 a disc or carrier 6 which is secured on the shaft 3 and rotates at a rate of speed determined according to the period 50 of operation desired. The shell 2 is provided with a coin intake chute 2^a and with a coin outlet or receiver 2^b. The disc or carrier 6 is provided with diametrically opposite coin pockets 7 substantially of duplicate

construction and arrangement. The disc is 55 preferably made of insulating material, and the opposite sides of the pockets are provided with contact bars 8 and 9.

The contact bar 8 is electrically connected to the ring 8' carried by the disc, and this 60 is surrounded by a ring 9' electrically connected to the contact bar 9. The coin slots 7 are radially disposed and have outer open mouths so that when one of the pockets is in a position vertically above the shaft 3, a 65 check or coin 10 can be deposited in the pocket and will serve to complete a circuit by concurrent engagement with the contact bars 8 and 9.

Constantly bearing upon the circuit rings 70 8' and 9' are brushes 8^a and 9^a which are shown as mounted upon a carrying arm or bracket 11 extending across the face of the coin carrier 6. The brushes 8^a and 9^a are connected to main service wires 12 and 13, 75 and these wires are electrically connected to the motor 5 and to a switch coil 14; the switch circuit and the motor circuit being shown as in parallel. The motor circuit includes the armature actuated switch arm 15 80 which is disposed adjacent to the coil 14 so that when a coin is deposited in the uppermost coin pocket, a circuit is instantly closed in the main wires 12 and 13 and the coil 14 is energized and the switch arm 15 85 attracted with the result that the motor circuit 5^a is closed and the motor is started.

The operation of the motor serves through the transmitting and speed reducing mechanism 4 to very slowly rotate the shaft 3 and 90 the coin carrier 6. The coin is retained in the pocket as it passes under the center of the shaft 3 by the overhanging wall of the shell 2, and as the coin reaches a position substantially vertically below the shaft 3, it 95 is then clear of the shell 2 and may drop out through the shell opening 2^c. As the coin clears the shell and falls, the circuit is automatically broken.

It is a feature of the invention to provide 100 for the continuance of the current flowing to the motor should the carried coin 10 break contact across the contact bars 8 and 9 as may occur when the coin moves down toward the exit 2^c. To that end, there is provided adjacent the exit 2^c a contact finger or blade 16 extending inwardly and being designed to engage a contact plate 17 of which there is one 105

arranged to one side of each of the contact bars 9 so that as the coin is carried to its lowermost position, the contact plates 17 respectively engage the finger 16. Circuit is made between the contact plates 17 and the ring 8' by a short circuit connection 18. The finger 16 is short circuited as to the wire 13 by a cross connection 19. From this it will be seen that as each coin is brought down below the center of the shaft 3, the motor circuit is maintained complete by the engagement of the contacts 17 with the contiguous finger 16 even though the circuit closing coin 10 may break circuit contact with the carrying bars 8 and 9.

After the coin has been inserted and the motor circuit closed, the motor will be operated for a period of time determined by the length of time it requires to carry an inserted coin from the uppermost position to its lowermost position in the shell. As the coin carrier 6 moves around, the circuit will be maintained until the contact plates 17 respectively move out of contact with the finger 16 and at that instant the switch coil 14 will be deenergized and the switch arm 15 released and the circuit broken.

Various modifications and changes may be resorted to within the spirit of the invention as claimed.

What is claimed is:

1. In a circuit controlling means, a motor and its circuit and a switch in said circuit, an insulated token carrier having opposite coin recesses and spaced contacts secured to the token carrier in said recesses and electrically connected to a second circuit, means in the second circuit for closing the switch, and driving means connecting said motor and said carrier, whereby an inserted token closes the second circuit to start the motor and the carrier is driven thereby.
- 40 2. In a coin controlled circuit closer, a car-

rier having rings for constant contact with terminals of the given circuit, diametrically opposite sets of coin receiving contact members on said carrier, said members connected to the circuit rings on the carrier, the circuit being closed by an inserted coin engaging the opposed members of a set.

50 3. In a coin controlled circuit closer, a carrier having rings for constant contact with terminals of the given circuit, diametrically opposite sets of coin receiving contact members on said carrier, said members connected to the circuit rings on the carrier, the circuit being closed by an inserted coin engaging the opposed members of a set, and an auxiliary short circuit device for each set of members.

60 4. The combination with a washing machine motor, of a circuit for said motor and an electrically operated switch in said circuit, an insulated token carrier having coin recesses and spaced contacts secured to the token carrier in said recesses, a second circuit electrically connected to said contacts, means in the second circuit for closing said switch, and driving means connecting said motor and said carrier, whereby an inserted token closes the second circuit to start the motor and the carrier is driven thereby.

70 5. In a coin controlled circuit closer, an insulated token carrier having a plurality of recesses, electric terminals secured to each recess, circuit rings connected to the carrier, a connection from opposite terminals to each ring and an auxiliary short circuit comprising a plurality of contacts on the carrier, a lead therefrom to a ring, and a fixed contact leading to the opposite side of the circuit.

75 In testimony whereof we have signed our names to this specification.

ARTHUR W. HARRISON.
FLOYD O. CHAFFEE.
